No. 704,125.

Patented July 8, 1902.

W. T. SEDDON.

BATTERY.

(Application filed July 20, 1901.)

(No Model.)

UNITED STATES PATENT OFFICE.

WILLIAM THOMAS SEDDON, OF MINERSVILLE, PENNSYLVANIA.

BATTERY.

SPECIFICATION forming part of Letters Patent No. 704,125, dated July 8, 1902.

Application filed July 20, 1901. Serial No. 69,113. (No model.)

To all whom it may concern:

Be it known that I, WILLIAM THOMAS SEDDON, a citizen of the United States, residing at Minersville, in the county of Schuylkill and State of Pennsylvania, have invented a new and useful Battery, of which the following is a specification.

This invention is an improved construction of electric battery, the object being to provide 10 an exceedingly cheap and simple construction of battery which shall have a greater voltage than batteries now in common use and one in which the polarization will be reduced to a minimum.

15 With these objects in view the invention consists in the peculiar construction of the various parts and in their novel manner of combination or arrangement, all of which will be fully described hereinafter and pointed 20 out in the claim.

In the drawings forming part of this specification, Figure 1 represents a battery constructed in accordance with my invention, part of the casing being broken away and the 25 top removed. Fig. 2 is a sectional elevation. Fig. 3 is a sectional elevation taken on a plane at right angles to the section shown in Fig. 2. Fig. 4 is a detail perspective view of the carbon electrode. Fig. 5 is a top plan view. 30 Fig. 6 is a detail perspective view showing the top of the zinc electrode.

In carrying out my invention I employ a case A, which is preferably constructed of hard rubber or some similar suitable material. Grooved strips B are arranged at regular intervals upon opposite sides of the case A, said strips being formed integral with the case or attached thereto, as preferred, said strips being of a non-corrosive and non-conducting material. These strips serve as guides for the zinc plates C, said plates being formed with shoulders C' at their upper ends, which rest upon the upper ends of the strips B, and thereby support the plates within the 45 case A. A wire C² is connected to one of the shoulders C', and the series of wires C² are

united to a common conductor-wire C³, as most clearly indicated in Fig. 1. The carbon electrodes D are arranged alternately between the series of zinc plates C, said carbon electrodes being made hollow for the purpose of receiving a chrome-salt solution. These carbon electrodes are also formed with shoulders D', into which are inserted the ends of the wires D², said wires D² being connected by a 50 common conductor-wire D³, thereby providing proper terminals for the battery. These shoulders D' also serve to support the electrode D, said shoulders resting upon the upper edges of the strips B. The zinc plates are 55 formed with any desired number of perforations C⁴ to permit circulation of the exciting fluid with which the case is filled. The shoulders upon the zinc and carbon electrodes support the said electrodes within the case a 60 short distance above the bottom, and a discharge-cock E is arranged at one side of the case adjacent to the bottom for the purpose of drawing off the liquid when desired.

It will thus be seen that I provide an exceedingly simple construction of battery, and practical demonstration has proven that the battery constructed in this manner is of exceedingly strong voltage and has a very small internal resistance.

Having thus fully described my invention, what I claim as new, and desire to secure by Letters Patent, is—

In a battery the combination with a cell or case having vertically-grooved strips arranged upon opposite sides, of the zinc plates arranged in the said groove and having shoulders at their upper ends adapted to rest upon the strips, and the carbon electrodes having shoulders at their upper ends, said carbon electrodes being hollow and adapted to receive a depolarizing solution, substantially as set forth.

WILLIAM THOMAS SEDDON.
